UNITED STATES PATENT OFFICE

2,141,827

DEVICE FOR DISTANT FIRING OF
EXPLOSIVE CHARGES

Marcel Schlumberger, Paris, France, assignor to
Societe de Prospection Electrique, Procedes
Schlumberger, Paris, France, a corporation of
France

Application January 24, 1936, Serial No. 60,727
In France November 16, 1935

10 Claims.

(Cl. 102—1)

In boring or other operations for working petroleum beds it may happen that it is necessary to fire successively a plurality of explosive charges at a distance and at depths which may be greater than 3,000 feet. This is particularly the case when it is intended to take cores or samples on the lateral wall of bore holes by means of a device such as described in U. S. Patent No. 2,055,506, September 29, 1936, for a Core taking device. It is also the case when it is intended to perforate the wall of a casing at the level of underground petroleum layers for working those layers by means of bullet perforators of any known type. In both cases the problem to be solved consists in making it possible to fire successively, at will and with any single given device (sample-taking device or perforator), the various gun-powder or explosive charges serving for the ejection of the bullets, and this by means of a single electrical conductor for controlling those successive firing operations.

The present invention relates to a device whereby this result may be attained in a simple and efficient manner, and without danger, by means 25 of resisting electric wires imbedded in the mass of gun-powder or explosive and heated by an electric current. However, the application of the present invention is not limited to the above mentioned cases but can be extended to other cases 30 where successive firings are to be effected at a distance.

The term "filament" will be used herein to designate the resisting electric wires imbedded in the explosive or in the gun-powder and the heating 35 of which causes the desired deflagration, although these wires are not necessarily caused to melt during the passage of the current or even under the action of the explosion. On the other hand, the expression "to blow up by means of a filament" will be used for the operation consisting in 40 causing a current to pass through the filament, sufficient for causing the deflagration in the corresponding chamber.

It has been already proposed, in the above mentioned patent and for solving this problem, to arrange in the various detonation chambers filaments having different characteristics and mounted in parallel between an insulated conductor body and the mass formed by the body of 45 the device itself arranged in the conductive mud of the bore hole. By causing increasing current intensities to pass through this conductor, the filaments are successively and selectively blown up. In practice this arrangement has been found 50 defective, for as soon as the first shot is fired the

conductive mud in the bore hole enters, by the force of its own pressure, the chamber where the deflagration has taken place and connects the line with the ground at the point where the filament has been blown up. Thus it is impossible to blow up the next filament.

It is the main object of the present invention to provide a remedy for this inconvenience and to that end detonating filaments of progressively decreasing heating capacities, for instance of increasing sizes in cross-section, are connected in series in the electric circuit, which can comprise only a single conductor with its return conductor, one of said filaments being placed in each explosion chamber. In the case of boring works and 10 of filaments which are effectively blown up the connection with the ground which occurs at the point where each deflagration has occurred ceases to be detrimental, as in the foregoing case, and on the contrary the same is indispensable, since 15 it is that which automatically re-establishes the interruption of the circuit through the ingress of the conductive mud into the corresponding detonation chamber.

If this grounding does not occur readily it is 25 possible to provide furthermore, according to this invention, devices adapted to cause an effective grounding under the action of the deflagration itself. These devices can operate, for instance, through direct engagement—under the action of 30 the pressure caused by the deflagration and if necessary with the obliteration of an intermediate insulation—of the conductor leading to each filament with one of the walls of the corresponding detonation chamber.

The present invention offers the advantage of 35 requiring only a single conductor, not only for connecting the point from which the deflagrations are controlled (above ground, for instance) with the device in which the deflagrations are produced (in the bore hole and at any depth), but even in the body of this device for causing the successive firings of a plurality of charges; as a 40 result whereof the construction and the assembly of the device are simplified.

In practice and because of the range of filaments which can be used, it will be easily possible to control four, five or more successive deflagrations by means of a single conductor.

On the other hand, as the organizations which 50 effect boring operations have generally at their disposal cables with several conductors, it will be possible, according to the invention, to provide devices (perforator or sample-taking device or the like) with a certain number of charges which can 55

be fired separately through each of the several conductors of the cable.

Other features of the invention will appear from the following description.

5 In the appended drawing several embodiments of the invention have been shown diagrammatically by way of non-limitative examples.

In this drawing:—

10 Figure 1 is a diagrammatical view showing the connection of filaments in series according to the invention.

Figure 2 is a longitudinal sectional view of a bullet perforator according to the invention.

15 Figure 3 is a longitudinal sectional view of a bullet sample-taking device according to the invention.

20 Figures 4 and 5 are respectively an enlarged cross sectional view and an enlarged profile view of a detail of the device shown in Figure 3.

25 In Figure 1, 1 is the insulated electric conductor which connects the point at which the firing is controlled (above ground, for instance) to the point where the firing must be effected (sample taking device or perforator, for instance, 30 immersed in the mud of a bore hole). In circuit with this insulated conductor are mounted in series a plurality of filaments, four for instance (3, 4, 5, 6); one of said filaments being located in each of the explosion chambers, and 35 said filaments being progressively of increasing diameter from one end to the other of the series, as shown in Fig. 1. The lower end of the lower filament 3 is grounded at 2; the ground mass being formed, for instance, by the metal body of the device itself which, being immersed in the 40 conductive mud, insures a good grounding. If the conductor 1 is then connected with one of the poles of a source of current, the other pole of which is grounded, so as to cause currents of successively increasing intensities to pass 45 through this conductor, filament 3 is first blown up, thus causing an explosion in one of the chambers. This explosion automatically causes, through the rushing into the explosion chamber of the conductive mud, for instance, the 50 grounding of the end of the filament 4 at 7. Then, by causing a current of a stronger intensity to pass, the filament 4 is blown up in its turn, thus causing an explosion in the corresponding chamber, followed by the grounding of the filament 5 at 8, and so on.

Figure 2 shows a bullet perforator of the type described in co-pending application for patent for a Core taking device, Serial Number 60,725, 55 filed January 24, 1936. The perforator comprises a cylindrical steel block 11 in which are annular detonation chambers 12, 13, 14 and so on, one beneath the other. Into these detonation chambers are screwed the tubes 15 which form 60 the guns serving to eject perforating bullets 16. The mouths of these guns are not located one directly beneath the next above, but are preferably disposed helically around the cylindrical body. The explosive is placed in the chambers 65 12, 13, 14 which enclose each one of the gun tubes 15, and in these chambers the filaments are located. Inasmuch as these filaments progressively decrease in cross section from the topmost downward, as shown in Fig. 1, the resistance 70 thereof correspondingly increases in the same order. The filament of the lower chamber is connected at its lower end with the mass of the cylindrical body 11. The several filaments 75 are connected with one another and with the

current supplying conductor through conductive devices which will be now described.

As shown in Fig. 2, the chambers 12, 13, 14 are in communication by vertical bore holes, in which are placed the connecting conductors. 5 These are formed, as shown, each of two plugs 17, 18, inserted or screwed one into the other so as to leave an annular space between them and the wall of the containing hole. But, of course, any other construction suitable for the purpose 10 may be adopted. Each pair of plugs has two valve-heads 19, 19', one at each end, which rest when closed upon a valve-seat, 20 or 21, formed in the metallic body 11 and coated with a rubber solution, or equivalent insulating substance 20', 15 21', which insures electrical insulation of the conductor 17—18. Thus in each explosion chamber are two valve-heads, one at the top and the other at the bottom thereof, the two being electrically connected together by the detonating 20 filament 35. Valve-head 19' in the upper explosion chamber is attached directly to the current supplying cable 1, which is suitably insulated and which serves not only to supply the detonating current but also to support the entire body 11.

The apparatus being immersed in the quasi fluid mud of the drill hole at the level where it is to be used, if current of the proper intensity is supplied to conductor 1, the filament of 30 smallest cross section, which is in the lowermost chamber, is blown, causing deflagration of the explosive in that chamber and the consequent expulsion of bullet 16 from gun 15 of that chamber. On the other hand, this explosion forces 35 the valve-heads 19, 19' of that chamber against their respective seats, thus crushing down the rubber solution 20', 21' and establishing metallic contact between the valve-heads and their seats. After the expulsion of the projectile the mud 40 in the bore hole, being under high pressure, forces its way into the tube of the gun 15 and into the explosion chamber, filling the same and thus insuring the grounding of the upper valve-head 19'. If then a current of greater intensity than 45 the first detonating current is sent through conductor 1, the second filament from the bottom will be blown, thereby exploding the charge in the corresponding chamber and causing a repetition of the above described phenomena; and so 50 on.

In Figure 3, which shows an embodiment of a bullet sample-taking device as described in the above mentioned patent application, Serial Number 60,726, the firing is effected in a similar manner. However, due to the presence in the detonation chamber of devices such as the cable or cables retaining the bullet, or because this detonation chamber is located behind the axis $x-y$ of the sample-taking device, it may be that 55 transmission of the current is not possible along said axis $x-y$. In that case insulated conductors 23, 24, 25 may be provided, which supply current to the valve heads 26 and 30 arranged as previously described in the bottom of each detonation chamber such as 27. Openings are provided in the cylindrical body 11 of the sample-taking device in order to permit the mounting of these different insulated members and these openings are closed either through threaded plugs 28 or 60 through screwed pieces 29.

The valve heads 26 and 30 which are, as previously described, insulated from the body of the device 11 by a rubber solution, for instance, come to rest at their edge (Figures 3, 4 and 5) against 70 75

metal pieces 31 and 32 in form of an arc of a circle, said metal pieces being applied against an annular piece of cardboard 33 mounted on the bottom of the detonation chamber 27. The firing filament 35 is directly connected with the annular pieces 31—32 (Figure 4).

As in the foregoing case, the filaments 35 are of progressively increasing diameter from the lowermost upwards, so that the deflagrations are produced successively from the bottom to the top when sending increasing current intensities. Under the action of the deflagration produced in one of the chambers, the ejection of the bullet causes, as previously described, the rushing in of 5 the mud which then seats the valve head 26.

In order to insure a still more efficient seating of the valve heads a hole 34 (Figs. 4, 5) may be provided in the piece of cardboard 33 at the place where it is covered by the conductor element 31. Under the action of the deflagration, the material 0 of the element 31 which lies opposite the hole 34, is pressed in or bulged and thus brought into contact with the metal bottom of the detonation chamber 27, thus insuring a perfect seating.

Of course, many changes can be made in the above described devices without departing from the scope of the invention. Furthermore, the invention can be applied to systems of sample-taking device or perforator other than those 5 herein described.

What I claim is:

1. In a device for successively firing a plurality of explosive charges at a distance through electrical means, a series of chambers each containing an explosive charge, a filament in each chamber surrounded by the explosive charge, the successive filaments being of a sensitiveness varying in the same direction from one filament to the next, means for connecting electrically the successive filaments in series, so as to form an electric circuit, and means for passing electric currents of progressively increasing intensities through the filaments.

2. In a device for successively firing a plurality of explosive charges at a distance through electrical means, a series of chambers each containing an explosive charge, a filament in each chamber surrounded by the explosive charge, the filaments being of progressively increasing diameters, means for connecting electrically the successive filaments in series so as to form an electric circuit, and means for passing electric currents through the filaments.

3. In a device for successively firing a plurality of explosive charges at a distance through electrical means, a series of chambers each containing an explosive charge, a filament in each chamber surrounded by the corresponding explosive charge, the filaments having different and progressively increasing heating capacities, means for connecting electrically the successive filaments in series, so as to form an electric circuit, and means for passing electric currents of progressively increasing intensities through the filaments.

4. In a device for successively firing a plurality of explosive charges at a distance through electrical means, a series of chambers each containing an explosive charge, a filament in each chamber surrounded by the explosive charge, the filaments being of progressively variable heating capacity, means for connecting electrically the suc-

cessive filaments in series so as to form an electric circuit, with return to the mass, means for passing electric currents through the filaments, and means for automatically grounding the circuit at the point where an interruption thereof is produced through the melting of the filament after each explosion.

5. Apparatus for electrically firing successively at a distance a plurality of explosive charges, said apparatus comprising: a metallic supporting body adapted for immersion in a quasi fluid medium under high pressure, such as the mud of a bore hole; a series of chambers for containing each an explosive charge; an electric circuit for controlling the explosions by means of a single 10 conductor; filaments of progressively increasing size, one in each of said chambers and connected in series in said circuit; means for automatically effecting the grounding of said circuit at the point where each explosion takes place, said 15 means being actuated by the inrush of said quasi fluid medium to effect contact of said conductor with the body of the apparatus.

6. Apparatus for electrically firing successively at a distance a plurality of explosive charges, 25 said apparatus comprising: a metallic supporting body adapted for immersion in a quasi fluid medium under high pressure, such as the mud of a bore hole; a series of chambers for containing each an explosive charge; an electric circuit for 30 controlling the explosions by means of a single conductor; filaments of progressively increasing size, one in each of said chambers and connected in series in said circuit; an insulating substance 35 between the body of the apparatus and said conductor at its entrance into and at its exit from each explosion chamber; means for automatically grounding said conductor at the point where each explosion takes place, said means being actuated by destroying said insulation and thereby effecting contact of said conductor with said metallic body.

7. Apparatus as specified in claim 6 wherein the means for automatically grounding the conductor at the point where an explosion occurs 45 comprising valve-heads for each chamber where the conductor enters and leaves it; an interposed insulating substance; and actuating means for bringing said valve-heads into such forceful contact with their respective seats as to destroy the 50 interposed insulation.

8. Apparatus as specified in claim 6, wherein the means for grounding the conductor at the point where an explosion occurs comprises valve-heads for each chamber placed where the conductor enters and leaves the same, and a pair of 55 plugs fitted together for connecting the valve-heads of adjacent chambers.

9. Apparatus for electrically firing successively at a distance a plurality of explosive charges, 60 said apparatus comprising a cable composed of a plurality of electrical conductors, each of said conductors having in its circuit a series of detonating filaments of progressively increasing sizes.

10. Apparatus for electrically firing successively at a distance a plurality of explosive charges, said apparatus comprising an electric circuit and a series of detonating filaments forming part of 70 said circuit, said filaments having different and progressively decreasing capacities.

MARCEL SCHLUMBERGER.
